UNITED STATES PATENT OFFICE.

THOMAS F. CHARLTON, OF MEADVILLE, PENNSYLVANIA, ASSIGNOR TO
KEYSTONE VIEW COMPANY, A CORPORATION OF PENNSYLVANIA.

VIEW-HOLDER.

No. 827,786.

Specification of Letters Patent.

Patented Aug. 7, 1906.

Application filed November 14, 1905. Serial No. 287,247.

To all whom it may concern:

Be it known that I, THOMAS F. CHARLTON, a citizen of the United States of America, and a resident of the city of Meadville, county of 5 Crawford, and State of Pennsylvania, have invented certain new and useful Improvements in View-Holders, of which the following is a specification.

The present invention relates generally to 10 stereoscopes, and has more particularly reference to an improved view-holder.

The object of the invention is to produce a view-holder of an inexpensive character and which at the same time will be strong and 15 rigid enough to prevent any torsional twist as it is moved back and forth on the shaft of the stereoscope.

To this end the invention comprises a view-holder composed of wire bent into a central 20 loop through which the shaft of the stereoscope is adapted to extend and terminating in a grasping portion underneath the said shaft, the said wire extending from said loop to form a cross-bar terminating in end guides 25 formed by substantially parallel strands of wire for the reception of the view.

In the particular form followed it is preferable to have two lengths of wire, each bent up into substantially parallel strands to form 30 end guides for the reception of the view and extending toward a common central portion, where the strands of both lengths run substantially parallel and are bent downwardly and back, forming a loop through which the 35 shaft extends, while the free ends of the strands converge at a common point underneath the shaft and form a downwardly-projecting grasping portion.

In the prior art where parallel strands of 40 wire have been used to form the end guides and cross-bar of view-holders it has been customary to reinforce the said cross-bar and end guides by means of metallic plates extending from one strand to the other and 45 flanged over the same, so as to give the proper strength and rigidity to the structure to prevent any torsional twist and to form a support for the lower edge of the view.

Another object of the present invention is 50 to dispense with these reinforcing-plates; and to this end the improved view-holder is composed of a central portion, preferably, but not necessarily, of wire, adapted to slide on the

shaft of the stereoscope, together with substantially parallel strands of wire formed into 55 end guides extending from the central portion, the said parallel strands of wire being twisted together at a point intermediate the central portion and end guides to form a support for the lower edge of the view and to prevent torsional twist.

In the accompanying drawings is shown the preferred form of the invention; but it will be understood that changes in construction may of course be made and the wire bent 60 differently without passing beyond the scope of the invention.

In the said drawings, Figure 1 is a perspective view of the view-holder embodying the invention shown in position on the shaft of 70 the stereoscope. Fig. 2 is a top plan view of the central loop. Fig. 3 shows a section taken on line 3 3 of Fig. 1 through the shaft.

Similar characters of reference indicate corresponding parts in the different figures. 75

1 and 2 indicate the two lengths of wire used in bending up the view-holder. As will be seen, each of the said lengths of wire is doubled on itself and properly shaped into parallel strands 3 and 4, so as to form end 80 guides 5 for the reception of the view. From these end guides the strands extend as a cross-bar preferably substantially parallel toward the central portion, where both strands of each length of wire run parallel with the 85 strands of the other length of wire and are bent downwardly, as at 6, and then back, as at 7, converging toward a common point 8, where they are suitably fastened together by being twisted up, as shown, or by being soldered, as indicated in the drawings by reference-number 9, or they may be fastened together in any other way found suitable.

The parallel strands of each length of wire are preferably twisted together, as indicated 95 at 10, at a point intermediate the end guides and the central loop, this tending to increase the strength of the structure and insuring the view being presented at right angles to the angle of vision, besides forming a support for 100 the lower edge of the view.

It is evident that if the wire loop is a little too large for the wooden shaft it would not stay in its place, and for this reason it is preferable that the wire should be bent down at 105 the points 6 7 8, whereby the wire will have

to be forced back again when the cross-bar is inserted on the shaft and would therefore fit snugly on the same.

What is claimed is—

5. 1. As a new article of manufacture, a view-holder for stereoscopes composed of wire bent into substantially parallel strands forming a cross-bar and end guides for the view, the said parallel strands being bent back at 10 the central portion of the view-holder to form a central loop through which the shaft of the stereoscope extends.
15. 2. As a new article of manufacture, a view-holder for stereoscopes composed of wire bent into substantially parallel strands forming a cross-bar and end guides for the view, the said parallel strands being bent back at the central portion of the view-holder to form a central loop through which the shaft of the stereoscope 20 extends, said strands having their free ends formed into a grasping portion underneath the shaft.
25. 3. As a new article of manufacture, a view-holder for stereoscopes composed of wire bent into substantially parallel strands forming end guides for the view, the said parallel strands being bent back at the central portion of the view-holder to form a central loop through which the shaft of the stereoscope 30 extends.
35. 4. As a new article of manufacture, a view-holder for stereoscopes composed of wire bent into substantially parallel strands forming end guides for the view, the said parallel strands being bent back at the central portion of the view-holder to form a central loop through which the shaft of the stereoscope 40 extends, said strands having their free ends formed into a grasping portion underneath the shaft.
45. 5. As a new article of manufacture, a view-holder for stereoscopes composed of wire bent into a central loop through which the shaft of the stereoscope extends and from which central loop the wire extends in substantially parallel strands terminating in end guides for the reception of the view.
50. 6. As a new article of manufacture, a view-holder for stereoscopes composed of wire bent 50 into a central loop through which the shaft of the stereoscope extends and provided with a downwardly-extending grasping portion, and from which central loop the wire extends in substantially parallel strands terminating in end guides for the reception of the view.
55. 7. As a new article of manufacture, a view-holder for stereoscopes composed of two lengths of wire, each bent into substantially parallel strands forming end guides, and extending toward a common central portion where the strands of both lengths run substantially parallel and are bent downward and back forming a loop through which the shaft extends.

8. As a new article of manufacture, a view-holder for stereoscopes composed of two lengths of wire, each bent into substantially parallel strands forming end guides, and extending toward a common central portion where the strands of both lengths run substantially parallel and are bent downward and back forming a loop through which the shaft extends, and converge at a common point into a downwardly-projecting grasping portion.

75 9. As a new article of manufacture, a view-holder for stereoscopes composed of wire bent into substantially parallel strands forming a cross-bar and end guides for the view, the said parallel strands being bent back at 80 the central portion of the view-holder to form a central loop through which the shaft of the stereoscope extends and twisted together at a point intermediate the said loop and end guides.

85 10. As a new article of manufacture, a view-holder for stereoscopes composed of wire bent into substantially parallel strands forming a cross-bar and end guides for the view, the said parallel strands being bent 90 back at the central portion of the view-holder to form a central loop through which the shaft of the stereoscope extends and twisted together at a point intermediate the said loop and end guides, said strands having their 95 free ends formed into a grasping portion underneath the shaft.

11. As a new article of manufacture, a view-holder for a stereoscope composed of wire bent into parallel strands to form end 100 guides for the reception of the view, the said wire extending from said end guides and being bent up to form a central loop through which the shaft extends.

105 12. As a new article of manufacture, a view-holder for a stereoscope composed of wire bent into parallel strands to form end 110 guides for the reception of the view, the said wire extending from the said end guides and being bent up to form a central loop, the parallel strands being twisted together at a point intermediate the central loop and end guides.

115 13. As a new article of manufacture, a view-holder for a stereoscope composed of wire bent into parallel strands to form end 115 guides for the reception of the view, the said wire extending from said end guides and being bent up to form a central loop through which the shaft extends, the ends of the strands terminating in a downwardly-extending grasping portion underneath the shaft.

120 14. As a new article of manufacture, a view-holder for stereoscopes, composed of wire bent into a central loop for the reception of the shaft of the stereoscopes, the said wire extending from said loop on both sides 125 to form a cross-bar terminating in end guides

formed by substantially parallel strands of wire for the reception of the view.

15. As a new article of manufacture, a view-holder for stereoscopes, composed of 5 wire bent into a central loop for the reception of the shaft of the stereoscope, the said wire extending from said loop on both sides to form a cross-bar terminating in end guides formed by substantially parallel strands of 10 wire for the reception of the view, the said strands of wire being twisted together at a point intermediate the end guides and the central loop.

16. As a new article of manufacture, a 15 view-holder for stereoscopes, composed of wire bent into a central loop for the reception of the shaft of the stereoscope, the free ends of the wire converging at a common point below the shaft and terminating in a 20 grasping portion, the said wire extending from said loop on both sides to form a cross-bar terminating in end guides formed by substantially parallel strands of wire for the reception of the view.

25. 17. As a new article of manufacture, a view-holder for stereoscopes, composed of two lengths of wire doubled on themselves so as to form substantially parallel strands shaped into end guides and extending toward 30 a central portion where the strands of both lengths are formed into a loop for the reception of the shaft.

18. As a new article of manufacture, a 35 view-holder for stereoscopes composed of two lengths of wire doubled on themselves so as to form substantially parallel strands shaped into end guides and extending toward a central portion where the strands of both lengths are formed into a loop for the reception 40 of the shaft, the free ends of the strands converging at a common point underneath

the shaft and terminating in a grasping portion.

19. As a new article of manufacture, a view-holder for stereoscopes, composed of 45 two lengths of wire doubled on themselves so as to form substantially parallel strands shaped into end guides and extending toward a central portion where the strands of both lengths are formed into a loop for the reception 50 of the shaft, the said strands being twisted together at a point intermediate the end guides and the loop.

20. As a new article of manufacture, a view-holder for stereoscopes, composed of a 55 central portion adapted to slide on the shaft of the stereoscope, substantially parallel strands of wire formed into end guides extending from the central portion, the said parallel strands being twisted together at a 60 point intermediate the central portion and the end guides to form a support for the lower edge of the view and to prevent torsional twisting.

21. As a new article of manufacture, a 65 view-holder for stereoscopes, composed of a central portion adapted to slide on the shaft of the stereoscope and having a grasping portion, substantially parallel strands of wire formed into end guides extending from the 70 central portion, the said parallel strands being twisted together at a point intermediate the central portion and the end guides to form a support for the lower edge of the view and to prevent torsional twisting.

Signed at Meadville, Pennsylvania, this 75
29th day of September, 1905.
